UNITED STATES PATENT OFFICE

JOHN H. DALEN, OF BERKELEY, CALIFORNIA

ROTARY SLICING MACHINE

Application filed March 3, 1928. Serial No. 258,754.

The invention forming the subject matter of this application relates to slicing machines, and particularly to the type of slicing machine which is used for slicing thin separator sheets such as are commonly used in wet-cell batteries.

The primary object of the invention is the provision of a machine which rapidly and accurately slices thin wet-battery separator sheets out of a comparatively large block of wood, said block being shaped to conform to the outline of the separator sheets, and in which machine a plurality of large blocks of wood are automatically fed to the slicing 15 blade.

A further object of the invention is the provision of adjusting means for a slicing machine by which the blades thereof may be minutely adjusted for slicing the separator sheets to the required thickness.

A still further object of the invention is the provision of a slicing disc in a slicing machine, said disc carrying the slicing blades in such a manner that the rotation of the disc 25 gradually impresses the blades with a carving motion into a wood block held thereabove, thereby causing the blades to delaminate smooth and thin separator sheets.

Another object of the invention is the provision of a slicing machine in which comparatively large bulks of semifinished material, such as blocks of wood, are held and fed by stationary guides against the top of a rotating disc, which disc carries blades 35 thereon, the blades being so curved as to pare off the lowermost stratum of said wood blocks by gradually and diagonally cutting thru the blocks; the line of cut being slightly diagonal to the direction of the grain of the 40 block and slightly diagonal to the edge of the block so as to secure a shearing cut approximately parallel with the grain and the edges of the block; said separator sheets to be so accurately cut as to have an even, over- 45 all thickness, the disc being so designed that the delaminated slices readily drop therefrom by their own gravity upon conveyors conveniently disposed below the disc.

Another object of the invention is the provision of blade-sharpening means on a slic-

ing machine which may be connected at will to the blade holder disc so as to be actuated by the turning thereof; said sharpening means being moved relatively to said disc in such a way as to follow precisely the cutting edge of a blade. 55

The essential features of the invention involved in the carrying out of the objects indicated are susceptible to modification, but a preferred embodiment of the invention is 60 shown in the accompanying drawings, in which:

Figure 1 is a side view of the device;

Figure 2 is a plan view of the slicing machine showing the feeding means partly cut 65 away;

Figure 3 is a fragmentary plan view of the blade-carrying disc;

Figure 4 is a sectional view taken on the line 4—4 of Figure 3; 70

Figure 5 is a plan view of Figure 4;

Figure 6 is a fragmentary, sectional view taken on the line 6—6 of Figure 2;

Figure 7 is a sectional view taken on the line 7—7 of Figure 3; 75

Figure 8 is a detailed view of the blade-sharpening mechanism, showing the same partly in section;

Figure 9 is a plan view of the blade-sharpening mechanism; and

Figure 10 is a sectional view taken on the line 10—10 of Figure 4.

In carrying out my invention, I employ a frame, designated in its entirety by the character A, which supports a slicing mechanism B. Above the slicing mechanism are disposed a plurality of feeding mechanisms C. 85

The frame A is illustrated as constructed of angle irons 6 disposed so as to form a polygonal base, at the corners of which uprights 7 extend vertically above the slicing mechanism B. The uprights are secured to the angle irons 6. The upper extremities of the upright members 7 are held together by brace members 8, said brace members extending substantially in parallelism with the top of the slicing mechanism B. The inside extremities of said brace members are secured to each other in such a manner as to leave an opening for the upwardly protruding parts of 90 95 100

the slicing mechanism B to be hereinafter described. Struts 9 are secured to the base and are disposed so that the inside extremities thereof converge and form a support for a bearing box 11.

5 The slicing mechanism B comprises a spoked wheel 12, a hub 13 depends downwardly therefrom into the bearing housing 11 and rests upon a ball bearing 14, as clearly 10 shown in Figure 6. In order to maintain the spoked wheel 12 in its position, a shaft 16 extends thru the hub 13, the wheel being rotatable around the shaft 16. The friction between the hub 13 and the shaft 16 is reduced by means of a ball bearing 17 in the 15 upwardly protruding portion 18 of the hub. The shaft 16 extends thru the bearing box 11 and is held against axial upward movement by a head 19 at the lower extremity 20 thereof. A bracket 21 secured to the inner ends of the bracing members 8 receives the upper end of the shaft 16 and maintains the same in its fixed position by means of a pin 22 extending thru the shaft 16 and thru said 25 bracket 21. A worm wheel 23 is fixedly secured to the hub 13 inside of the box 11 and is rotated by a worm 24 rotatably supported in the walls of said box. The worm 24, in turn, is rotated by an electric motor 26 from 30 which the power is transmitted to the worm 24 by any conventional transmission means such as a belt 27.

The wheel 12 has six spokes therein and in 35 every second space between the spokes a web 28 extends from one spoke to the next. A plate 29 is secured to said web 28 by means of screws 31. The web is so shaped as to conform to the outline of the stationary plate 29. One edge of the plate 29 is curved for the 40 purpose to be hereinafter described, and the curved edge 32 of the plate 29 determines the shape and the extent of the web 28. In every other space between the spokes, another set of stationary plates 33 is disposed, which 45 latter plate is secured to the spokes by means of screws. The plates 33 extend to the outside periphery of the spoked wheel 12, the inside edges of said plates 29 and 33 forming a hexagon or other polygon, depending on 50 the number of plates used. The plates 29 and 33 are on the same horizontal plane.

A blade-carrying plate 34 is secured to 55 wheel 12 and disposed at a higher level than the plates 29 and 33 and extends from the outside periphery of the wheel 12 toward the plate 29 so as to leave a clearance between the inside edge of the plate 34 and the curved edge 32 of the plate 29, said edges being parallel with each other. A slicing blade 36 60 is secured to the inside edge of the plate 34 in a manner clearly shown in Figure 7. The blade 36 is held against the inclined edge 37 of the plate 34 by means of a clamping block 38 which, in turn, is secured to the plate 34 65 by means of screws 39. When it is desirable

to adjust the blade 36, the screw 39 is loosened up, thereby permitting the manual adjustment of the blade. It is to be noted that the cutting edge of the blade 36 is approximately on the same level as the top surface of the plate 34 and that the edge of the blade is thus disposed at a higher level than the top surface of the plate 29, providing a clearance therebetween. A rim 41 on the wheel 12 is adapted to receive the adjusting means for moving the plate 34, thereby increasing or decreasing the space between the blade 36 and the plate 29 and the difference between the level of the plates 29 and 34. The plate 34 must be raised or lowered, and this adjustment of said plate 34 is accomplished by the adjusting mechanism, clearly shown in Figure 4. The adjusting mechanism is denoted in its entirety by numeral 42. At the shorter end of the plate 34, a correspondingly shorter adjusting mechanism 43 is disposed, and as the operation and structure of both adjusting mechanisms are identical, except for the dimensions thereof, the description of the structure of the adjusting mechanism 42 will be sufficient to explain the operation of both adjusting mechanisms.

The spoke of the wheel 12 has a depending lug 44 thereon, which is in alignment with a bearing 46, depending from the rim 41 of said wheel. In the bearing, a shaft 47 is supported and maintained in an axially fixed position by means of a shoulder 48 thereon and by a collar 49 at the opposite side of the lug 44. The shaft 47 is rotated by means of a hand wheel 51. In some cases, it will be desirable to shorten the outside end of the shaft so that the adjusting mechanism will not protrude beyond the outside periphery of the rim 41. In that case, any conventional means may be employed for rotating the shaft such as a square or polygonal socket in the end of the shaft, flush with the bearing 46, in which socket a crank may be inserted for rotating the shaft when adjustment of the plate is required.

A worm 52 is formed on the middle portion of the shaft 47, and it is always in mesh with teeth 53 on the underside of a wedge 54. The wedge 54 is guided in its movement by a dovetail groove 56 as it is clearly shown in Figure 10, the dovetail groove being cut into the spoke of the wheel 12, and being disposed so as to guide the wedge 54 radially and in a horizontal plane. The uppermost portion of the wedge is provided with a dovetail 57. A dovetail groove 58 is cut in the underside of the plate 34, the inclination of said latter groove being complementary to the inclined dovetail 57. When the shaft 47 is rotated, the worm 52 will cause the movement of the wedge 54 toward or away from the center of the wheel 12. The movement of the wedge in a horizontal plane causes the dovetail 57 to slide in

70

115

120

125

130

the dovetail groove 58. When the wedge is advanced toward the center of the wheel 12, the plate 39 will be raised thereby and vice versa.

5 In order to permit the use of similar graduations on both adjusting mechanisms 42 and 43, the wedge 54 and the corresponding inclination of the groove 58 are steeper in the adjusting mechanism 43 than in the 10 adjusting mechanism 42, thus, compensating for the change in the length of the adjusting mechanisms. In case it is found necessary to provide a more substantial support for the plate 34, a third support, incorporating the adjusting mechanisms heretofore described, may be disposed at an intermediate point between the adjusting mechanisms 42 and 43. It is also possible to provide a web below the plate 34 and render the same stationary and employ an 15 adjusting mechanism on the now stationary plates 29 and 33 for raising or lowering the same relative to the cutting edge of the blade 36, thereby adjusting the spacing therebetween.

20 25 Each of the feeding mechanisms C comprises a guide 60 secured to the bracing members 8. The guide 60 consists of a plate bent at right angles. As the slicing mechanism B is rotated in a contra-clockwise direction, 30 looking at Figure 2, the open side of the right angle guide points in a direction opposite to the rotation of the slicing mechanism so that the material guided thereby is pressed against the walls thereof by the rotation of the slicing 35 mechanism. Bearing brackets 61 extend from one of the walls of the guide 60. A shaft 62 is slidable in the bearing brackets 61. The downward movement of the shaft 62 is effected by the gravity thereof and is 40 limited by a collar 63 on the shaft abutting the upper face of the bracket 61. The lower end of the shaft 62 flanged as at 64, to which flange is secured a rectangular guide block 66 slideable on the guide 60. The machine in the illustration is designed to cut 45 rectangular battery separators. Therefore, both the guide and the guide block 66 are so shaped as to guide a rectangular wood block, not shown, from which the separator sheets 50 are to be delaminated. The guide block 66 conforms to the outline of the battery separator. In case any other shape of battery separator is desired, the shapes of the guide block 66 and the guide 60 are changed so as 55 to conform therewith.

In order to facilitate the slicing of smooth battery separator sheets, the wooden blocks, from which the separators are cut, may be steamed before being placed in the guide 60. 60 Then by raising the shaft 62 in the brackets 61, sufficient space is provided below the guide block 66 to permit the insertion of wooden blocks below the guide block 66; thus the steamed or otherwise prepared wooden 65 blocks are pressed against the stationary

plates 29 and 33 by the weight of the shaft 62, the flange 64, and the guide block 66. The raising of the shaft 62 is accomplished by means of a cord or cable 67 guided on a pulley 68 which is secured to a ceiling 69 of the building. The cable 67 is manually actuated and may be secured to a hook or any other means on the wall of the shop, not shown.

70 The slicing of the battery separators is accomplished as follows: The prepared wooden blocks are placed in the guide below the block 66 in the manner heretofore described, and they are held against the stationary plates 29 or 33. By starting the 75 motor 26, the wheel 12 is rotated in a contra-clockwise direction, as may be seen in Figure 2. As the plates 29 and 33 are on the same level, the plate 29 will readily slide under the 80 wooden block. The wider edge of the plate 29 slides first under the block so that the edge of the blade nearest to the rim 41 is brought first into contact with the outside edge of the 85 rectangular block. Further rotation of the wheel 12 causes the blade to further incise into the block. As the block is pressed against the lower plate 29, the thickness of the 90 cut is determined by the space between the cutting edge of the blade 36 and the top of the plate 29. The blade 36 is curved at such a radius that the outermost point thereof engages the outside edge of the block to be cut, while the innermost end of the cutting blade passes thru the inside edge of the block. The 95 rotation of the wheel 12 moves the blade 36 with a carving motion thru the whole cross-sectional area of the wooden block, thereby assuring a smooth cut, the line of cut being slightly diagonal to the direction of the grain of the block and slightly diagonal to the edge 100 of the block, thereby resulting in a shearing cut approximately parallel with the grain and the edges of the block. As the spacing between the cutting blade 36 and the top of the plate 29 is accurately adjusted, the whole 105 length of the slice cut off by the blade will be accurate and of even thickness throughout.

110 Immediately when the outer end of the blade 36 cuts into the outer edge of the block, the delaminated portion of the block enters 115 into the spacing between the blade 36 and the top of the plate 29. The curved edge 32 of the plate 29 is beveled as at 76, and the battery separator, sliced off by the blade 36, is directed downwardly thereby. By the time 120 the blade 36 completes the cut thru the block to the inner edge thereof, the whole slice of the battery separator sheet is below the blade, and when completely separated from the block, it slides thru the space by its own 125 gravity. The thickness of the battery separator sheet is accurately determined by the adjustment of the blade 36 by means of the adjusting mechanisms 42 and 43.

Conveyors 77 are disposed below the slic-

ing mechanism B, each conveyor 77 being opposite to a feeding mechanism C so that when the battery separator sheets slide out of the slicing mechanism thru the space between the blade 36 and the plate 29, the separator sheets drop on the conveyor 77. One of said conveyors is shown in detail, while the position of the other four conveyors is indicated in dash-and-dotted lines in Figure 2. 5
10 The conveyors shown in the present illustration are manually operated by means of a hand wheel 78 rotating the opposite drums 79 by means of an endless belt 80. The battery separators are carried on the belt 77 out from below the slicing mechanism so that they may be removed therefrom without necessitating the handling of the battery separators below the machine. It is to be understood that a continuous conveyor, especially designed for 15 the machine, may be employed to carry away the separator sheets from below the slicing mechanism. The conveyor 77 is shown as an illustration of the fact that the battery separators dropping thru the slicing mechanism are received by a conveyor, by which they are carried away from below the slicing mechanism.

The battery separators will be smoothly finished because of the fact that the blocks 30 are steamed or otherwise prepared and the blades are curved so as to gradually, but speedily, enter the blocks with a carving or shearing motion so that while the blade moves into the wooden blocks in a direction toward 35 the center of the slicing mechanism C, it also moves in an annular path so that the cut is nearly tangential, and nearly paralleling the grain of the block, thereby permitting the smooth cutting of the extremely thin separators without crimping the same.

A blade-sharpening mechanism, denoted in its entirety by the numeral 81, is adapted to accurately grind the edge of the blade 36 and to be guided along the said edge by the rotary 40 movement of the wheel 12 itself. The structure of the grinder is clearly illustrated in Figure 8 and comprises a rotating disc 82 made of carborundum or any other grinding material, said disc being rotated in the conventional manner by an electric motor 83.

A bearing sleeve 84 of the electric motor 83 is fixedly secured into a bracket 86, which bracket is formed with a dovetail 87 at the free end thereof. A traveler 88 has a groove 55 89 therein, complementary to said dovetail 87 in which said dovetail is slidable. In a lug 91 on the traveler 88 is a crank shaft 92. Said crank shaft is rotatable in the lug 91 and is held against axial movement by a shoulder 93 and a collar 94 thereon disposed at the opposite sides of the lug 91. A jack screw 95 forms one end of the crank shaft 92, said screw being in engagement with a threaded hole 97 in the dovetail 89. The turning of the crank shaft 92 causes the power of the

screw to be applied to the bracket 86 for raising and lowering the same in a vertical plane as guided by a dovetail groove 89. The movement of the grinding disc 82 in a horizontal plane is effected by the movement of the traveler 88 along a rail 98 which is fixedly secured to a bracing member 8. The dovetail 99 of the rail 98 slidably engages a dovetail groove 101 in the traveler 88. The traveler 88 is connected to the wheel 12 by means of a link 102, one end of which is pivotally secured to the traveler as at 103, the other end thereof being pivotally and removably secured at an eccentric point 104 on the wheel 12. 70 75 80

The grinding of the blade 36 is performed as follows: First, the slicing mechanism B is rotated until the inside end of the blade is below the grinding disc 82. The length of the link 102 determines the position of the grinding disc 82. Then, by turning the crank shaft 92, the jack screw 96 lowers the bracket 86 and the grinding disc 82 therewith until the same rests on the blade 36. Now, the starting of the motor 83 rotates the disc 82 in a horizontal plane so that the disc grinds the blade 36 to a level with the horizontal top of the blade-carrying plate 34. By manually rotating the wheel 12 in a clockwise direction, the blade 36 is gradually fed under the disc 82, and at the same time, the link 102 is moved by the eccentric mechanism 104 thereof. The rotating movement at said point 104 is transformed by the link 102 into a linear movement, sliding the traveler 88 on the rail 98. The location of the eccentric point 104 is so determined that the linear movement of the traveler 88 moves the grinding disc 82 so as to follow the curvature of the blade 36 when the blade is fed below the disc 82. By manually rotating the wheel 12 back and forth, the blade is fed under the rotating disc 82 from one end to the other until the cutting edge thereof is ground to the required sharpness. 90 95 100 105 110

It is apparent from Figure 7 of the drawings that the edge of the blade 36 and the top of the blade 34 are in a single plane. When the blade is worn down, before the regrinding takes place, the clamp 38 is loosened and the blade is pulled out from under the plate 34 to the desired extent. Then the clamp 38 is tightened, holding the blade in position while it is ground down by the aforesaid method to the level of the plate 34. 115

For the grinding of the lower face of the blade 36, the same grinder 81 is mounted on a curved guide (not shown) conforming to the radius of the blade. The bevel of the grinding disc 82 is brought into contact with the lower surface of the blade 36. Then the motor is started and the grinding device traverses the cutting edge of the blade as it is slid along its curved guide. This necessarily requires either the dismounting of the plate 120 125 130

34 with the blade 36 and the removing thereof to another fixture and mounting thereof, or the removal of plate 29 and the mounting of said curved guide in its place.

It will be recognized that a particularly compact device is provided to accomplish the above described method of slicing the extremely thin battery separator sheets; and one which combines accurateness with a ruggedness of construction and positiveness of operation, particularly adapted for its use. Being a unitary character, the device, after the adjustment of the blades, requires no further careful setting up and lends itself to effective application by the labor ordinarily available.

Although I have shown and described the preferred embodiment of my invention, it is to be understood that changes within the domain of mere form or construction or arrangement may be made by persons skilled in the art without involving any change in mode of operation or of function or of results described in the appended claims.

Having thus described my invention, what I now claim as novel and desire to secure by Letters Patent is:

I claim:

1. A slicing machine comprising a rotatable wheel having radial spokes, supporting plates supported by the spokes, adjustable plates supported by the spokes and in alternate relation to the first-named plates, cutting blades carried by the adjustable plates, stationary guides contiguous to the face of the plates and means for forcing an object within the guides into contact with the plates.

2. A slicing machine comprising a rotatable wheel having radial spokes, segmental plates affixed to the alternate pairs of spokes at a point intermediate the hub and the rim thereof, plates adjustable with relation to the plane of the fixed plates carried by the wheel and having cutting blades adjustably secured thereto, elongated guides having their ends in juxtaposition to the faces of the fixed plates, plunger shafts within the guides and means for retaining the plunger shafts at the limit of their movement in one direction.

3. A slicing machine comprising a rotatable wheel, segmental plates affixed to the alternate pairs of the spokes of the wheel, cutting blades carried by the spokes in the alternate spaces therebetween, said cutting blades being adjustable with relation to the plane of the fixed plates.

4. A slicing machine comprising a rotatable wheel, plates, the outer faces of which lie in the same plane and form a disc-like support, plates capable of vertical adjustment with relation to the plane of the support, means for reciprocally adjusting the movable plate journaled in dependent lugs carried by the wheel and a cutting blade carried by the movable plate.

5. A slicing machine comprising a rotatable wheel, plates the outer faces of which lie in the same plane and form a disc-like support, plates capable of vertical adjustment with relation to the plane of the support, screw-threaded means for reciprocally adjusting the movable plate journaled in dependent lugs carried by the wheel and a cutting blade carried by the movable plate.

6. A slicing machine comprising a rotatable wheel, supporting plates spanning the alternate spaces between the spokes of the wheel and fixedly related thereto, plates affixed to the spokes and spaced inwardly of the rim of the wheel interposed between the first-named plates, plates capable of reciprocal movement with relation to the inwardly spaced plates interposed between the outer curved surfaces thereof and the rim of the wheel, an adjustable cutter blade carried by the adjustable plates, inwardly tapering wedges supporting the adjustable plates and means for imparting reciprocal movement to the wedges.

7. A slicing machine comprising a rotatable wheel, supporting plates spanning the alternate spaces between the spokes of the wheel and fixedly related thereto, plates affixed to the spokes and spaced inwardly of the rim of the wheel interposed between the first-named plates, plates capable of reciprocal movement with relation to the inwardly spaced plates interposed between the outer curved surfaces thereof and the rim of the wheel, an adjustable cutter blade carried by the adjustable plates, inwardly tapering wedges supporting the adjustable plates and a worm gear for imparting reciprocal movement to the wedges.

8. A slicing machine comprising a wheel, plates spanning the alternate spaces between the spokes of the wheel, grooves within the spokes, wedges capable of reciprocal movement within the grooves, lugs depending from the spokes, a worm journaled in the lugs for imparting reciprocal movement to the wedges and a cutting blade supported by the wedges.

9. A slicing machine having a supporting frame, braces carried by the frame, a wheel having a dependent hub, a stationary shaft extending through the hub, a bearing surrounding the shaft, struts extending from the frame members and affixed to the bearing, a worm wheel carried by the hub and having a worm meshing therewith, plates spanning the alternate spaces between the spokes of the wheel and affixed thereto with their outer edges contiguous with the rim of the wheel, cutting blades carried by the plates, plates interposed between the first-named plates and affixed to the spokes of the wheel having their outer curved faces spaced from the rim of the wheel, plates capable of vertical adjustment with relation to the plane of the first-named

plates and means carried within the spokes of the wheel for imparting vertical movement to the movable plates.

10. A slicing machine having a frame, 5 braces connecting portions of the frame, a rotatable wheel journaled within the frame and below the braces, plates spanning the alternate spaces between the spokes and affixed thereto, cutting blades carried by the plates, 10 plates capable of vertical adjustment with relation to the plane of the first-named plates interposed therebetween, sharpening mechanism carried by one of the braces and capable of longitudinal reciprocal movement thereof, and a link eccentrically connecting the 15 sharpening mechanism and one of the spokes of the wheel.

11. A slicing machine having a frame, 20 braces connecting portions of the frame, a rotatable wheel journaled within the frame and below the braces, plates spanning the alternate spaces between the spokes and affixed thereto, cutting blades carried by the plates, plates capable of vertical adjustment 25 with relation to the plane of the first-named plates interposed therebetween, a sharpening mechanism carried by one of the braces and capable of longitudinal reciprocal movement thereof, and a link eccentrically connecting the 30 sharpening mechanism and one of the spokes of the wheel for positioning the sharpening mechanism with relation to the face of the cutting blade.

12. A slicing machine having a frame, 35 braces connecting portions of the frame, a rotatable wheel journaled within the frame and below the braces, plates spanning the alternate spaces between the spokes and affixed thereto, cutting blades carried by the plates, 40 plates capable of vertical adjustment with relation to the plane of the first-named plates interposed therebetween, sharpening mechanism carried by the braces and capable of longitudinal reciprocal movement thereof, 45 and a link eccentrically connecting the sharpening mechanism and one of the spokes of the wheel for automatically positioning the sharpening mechanism with relation to the cutting edge of the blade when the wheel is 50 rocked upon its axis.

13. A slicing machine having a frame, 55 braces connecting portions of the frame, a rotatable wheel journaled within the frame and below the braces, plates spanning the alternate spaces between the spokes and affixed thereto, cutting blades carried by the plates, plates capable of vertical adjustment with 60 relation to the plane of the first-named plates interposed therebetween, sharpening mechanism carried by one of the braces and capable of longitudinal reciprocal movement thereof, a link eccentrically connecting the sharpening mechanism and one of the spokes of the 65 wheel, and means for imparting reciprocal

vertical movement to the sharpening mechanism.

14. A slicing machine comprising a rotatable wheel, plates, the outer faces of which lie in the same plane and form a disc-like support, plates capable of vertical adjustment with relation to the plane of the support, screw-threaded means for reciprocally adjusting the movable plates journaled in dependent lugs carried by the wheel and a cutting blades carried by the movable plate with its respective ends spaced at unequal distances from the rim of the wheel. 70 75

15. A slicing machine comprising a rotatable wheel, plates, the outer faces of which lie in the same plane and form a disc-like support, plates capable of vertical adjustment with relation to the plane of the support, screw-threaded means for reciprocally adjusting the movable plates journaled in dependent lugs carried by the wheel and curved cutting blades carried by the movable plates and positioned eccentrically with relation to the axis of the hub of the wheel. 80 85

In testimony whereof I affix my signature. 90
